PAGE 2

FIG. 6

FIG. 5

Fig. 1 is a front elevational view of an action game device showing our new design;

Fig. 2 is a top plan view of Fig. 1;

Fig. 3 is a right side elevational view of Fig. 1;

Fig. 4 is a left side elevational view of Fig. 1;

Fig. 5 is a back elevational view of the new design;

Fig. 6 is a vertical sectional view taken along line 6-6 of Fig. 2; and

Fig. 7 is a vertical sectional view taken along lines 7-7 of Fig. 7.

The dominant feature of our design resides in the portions shown in full lines.

We claim:

The ornamental design for an action game device, as shown and described.
